(57) **CLAIM**

The ornamental design for a magazine loader, as shown and described.

DESCRIPTION

FIG. 1 is a top, front, right side perspective view of a magazine loader;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The evenly-spaced broken lines in FIGS. 1-7 depict portions of the magazine loader that form no part of the claimed design. The dot-dash broken lines define the bounds of the claim that form no part thereof.

1 Claim, 3 Drawing Sheets
